ATTORNEY

UNITED STATES PATENT OFFICE.

LOUIS G. JORDAN, OF COPALIS, WASHINGTON.

ADVERTISING DEVICE.

1,402,617.

Specification of Letters Patent.

Patented Jan. 3, 1922.

Application filed July 18, 1917. Serial No. 181,331.

To all whom it may concern:

Be it known that I, LOUIS G. JORDAN, a citizen of the United States, residing at Copalis, in the county of Grays Harbor and 5 State of Washington, have invented new and useful Improvements in Advertising Devices, of which the following is a specification.

The present invention relates generally to an advertising apparatus, comprehending 10 particularly a changeable exhibitor having installed therein a series of movable belts or aprons on each of which appears a series of unit images, whereby one of the images on each belt, when exhibited or displayed 15 through the visible opening of the casing, will collectively produce a complete picture.

One of the salient features of the present invention contemplates the provision of novel means for imparting to each of the 20 belts or aprons an intermittent movement, causing a different display on the respective series of unit images through the display opening of the casing to produce different complete pictures.

25 With the above and other objects in view, the invention consists in the novel features, details of construction and combination of parts which will hereinafter be more fully set forth, illustrated in the accompanying 30 drawings and pointed out in the appended claims.

The figure is a perspective view of an apparatus embodying my invention.

Referring more particularly to the accompanying drawing, in which like characters of reference refer to corresponding parts in the several views, a common drive shaft 17 is journaled in spaced standards 18.

Journaled in the standards 18 at a point 40 above the driven shaft is a drive shaft 19 carrying a pulley 20 over which is trained the drive belt 21 leading from the motor 22. On one end of the drive shaft 19 is a pinion 23 meshing with the toothed periphery 24 of 45 a yieldably supported disk 25. The disk 25 is mounted on the driven shaft 17 for a slightly horizontal sliding movement, having connected to its axis one of the end convolutes of a coil spring 27, as denoted by 50 the character 26, and to the opposite end convolute 28 of the spring is a flexible arm 29 keyed on the stub shaft 30 of the lowermost gear 31. Carried by the toothed disk 25 and projecting laterally therefrom is a 55 trip 32, which, owing to the provision of the

coil spring 27, will be tensionally brought into contact alternately with the spaced upright flexible posts 33 upon the completion of a half revolution of the disk 25, which in turn will flex the post 33 and cause the free 60 end of the arm 29 to be released from engagement with the horizontal abutting shoulder 34 of the post.

In briefly describing the operation of the invention, and assuming the parts constituting the apparatus are properly installed for use, the motor 22 is started, which in turn will operate the pulley 20 and impart movement to the disk 25 by the pinion 23 meshing with the notched peripheral edge thereof. 70 This movement will cause to be imparted to the trip 32 a rotary movement, which in turn will release the arm 29 from one of the posts, and upon a half revolution of the disk 25, will again cause the tensioning of the 75 coil spring 26, as at this point the said spring is untensioned by the throwing of the arm 29 into contact with the opposite post.

From the foregoing description, taken in connection with the accompanying drawings, 80 the advantages of construction and the method of operation will be readily apparent to those skilled in the art to which the invention relates, and while I have described the principles of operation of the invention, 85 together with the device which I now consider to be the best embodiment thereof, I desire to have it understood that the device shown is merely illustrative and that such changes may be made when desired as are 90 within the scope of the appended claims.

What is claimed as new, is:—

1. Means for operating a changeable exhibitor embodying a drive gear, a drive shaft, means for driving said shaft, an arm, 95 a member having a shoulder with which the arm engages for holding the latter against movement, resilient means operatively connecting the drive gear and said drive shaft, means for flexing said member to release the 100 arm therefrom.

2. Means for intermittently operating a changeable exhibitor embodying a driven shaft, a stub shaft, a spring interposed between said former and latter mentioned 105 shafts, an arm carried by the stub shaft, a member having a shoulder with which the arm engages for holding the latter against movement, and means for flexing said member to release the said arm therefrom.

3. Means for imparting an intermittent movement to a changeable exhibiter comprising a driven shaft, a stub shaft, a spring interposed between said former and latter 5 mentioned shafts, an arm carried by the stub shaft, a member having a shoulder with which the arm engages for holding the latter

against movement, a disk mounted on the driven shaft and provided with a trip adapted to engage with said member for 10 flexing the latter to cause the release of the arm therefrom.

In testimony whereof I affix my signature.
LOUIS G. JORDAN.
